SPRAY-DRIED, NON-CLOTTING, GRANULATED SOAP PRODUCT AND METHOD OF PRODUCING THE SAME

Irving Reich, West New York, and William A. Kelly, Teaneck, N.J., assignors to Lever Brothers Company, New York, N.Y., a corporation of Maine

No Drawing. Filed Dec. 20, 1955, Ser. No. 554,143

11 Claims. (Cl. 252—109)

The present invention relates to a soap product and to a method of producing the same, and more particularly to a spray-dried, non-clotting, granulated soap product and to a method of producing the same.

Granulated soap products are soaps which have been prepared for household use by slurring the soaps with water, spraying the slurry, and drying the droplets in heated air. They consist of tiny granules, more or less irregular in shape. Usually they include a few percent of inorganic and alkaline substances, such as sodium silicate and tetrasodium pyrophosphate, in addition to the soap. Granulated soap products of this type are widely used for household washing. One of the main advantages of this form of soap product is the relatively short time required in which water solutions or dispersions of soluble soaps may be obtained as compared with the time required to do so when using bars or sliced or chipped forms.

Conventional granulated soap products, however, show a tendency to lump together when thrown into hot water. Apparently the granules float on the surface, become pasty and sticky as the hot water wets and partially melts them, and then stick together in a coherent pasty mass or clot. These clots may vary in size from that of a grain of rice to that of a large thumb. Large clots may consist of a pasty surface layer with dry, unwet powder inside. Since the clots dissolve very slowly, the formation of clots delays proper sudsing and cleansing action. In addition, the clots are also unattractive in appearance. Furthermore, clotted soap products adhere to fabrics or surfaces being washed, in some instances leaving the surfaces smeared or blotched even after the washing and rinsing procedures have been completed.

The tendency of granulated soap products to form clots may be reduced if the soap is first dispersed in cold water and this dispersion is then poured into hot water. This, however, is an inconvenient extra operation. It is not easily accomplished in all types of mechanical washers. Furthermore, when it can be done it may also result in reducing the temperature of the hot water below that required for proper washing action.

The tendency of granulated soap products to clot may also be reduced by forming the granulate particles as irregular or scraggly particles rather than as puffed or hollow particles. An irregular or scraggly particle when poured into water will wet more quickly than a rounded or rounded and puffed particle possibly due to the larger area exposed to the water. Quick wetting increases the solubility rate and places a water film between the individual particles, thereby tending to prevent them from sticking together.

Granulated soap products of the type discussed above are ordinarily made from tallow and other animal fats. Tallow soap consists mainly of the mixture of the alkali metal salts of stearic, palmitic, and oleic acid. It is common, however, to include a limited proportion, up to about 20%, of coconut oil soap. This consists mainly of the mixture of the alkali metal salts of lauric and myristic acid. It is known that the presence of suffi-

cient coconut oil soap reduces the tendency of the granulated soap products to clot, because coconut oil soap due to its hardness dissolves rather than melting and gumming before solubilizing and because it is one of the most soluble of all soaps. However, coconut oil soap is considerably more expensive than tallow soap. In addition, to reduce clotting significantly, over about 40% of coconut oil soap is required. This is undesirable in view of the high cost. Furthermore, it is known that at the high temperatures often used in washing fabrics, coconut oil soap is a poorer soap than is tallow soap, so that the use of this large proportion of coconut oil soap will impair detergency.

U.S. Patent No. 2,388,632 to Byerly describes a method of reducing clotting by spray-drying the coconut oil soap and the tallow soap separately, and then mixing the two dried soaps mechanically. This permits some reduction in the total amount of coconut oil soap required to reduce clotting. However, an undesirably high proportion of coconut oil soap is still required. Also the requirements of spray-drying the two soaps separately and mechanically mixing the two after drying makes the process undesirably complicated and increase the cost of manufacturing operations. It is well known that a mixture of two different powders will tend to stratify in a container, especially when continually disturbed, as during freight transportation. For this reason, a mechanical mixture of this type is less desirable than a homogeneous product, wherein all grains have the same composition.

In an attempt to solve this problem of clotting the following test procedure was devised and employed in the examples set forth herein. The results obtained by this test procedure had correlated well with large scale test runs in washtubs. The procedure consisted of running 800 cc. of tap water at 125° F. into a 1000 cc. beaker. Ten grams of the granulated soap product was poured in a heap on the surface of the water. Stirring with a steel microspatula was begun immediately, using back and forth strokes the full width of the beaker, at the rate of 80 strokes per minute. The clotting was graded after 30 seconds and again after 60 seconds of stirring according to the following system:

Grade No.	Degree of Clotting
0	Soap completely dissolved.
1	A few specks floating.
2	A number of clots of the size of rice grains.
3	Many clots, some as large as peas.
4	Nearly all the soap still floating as large clumps.

The clotting score is the total of the 30 and 60 second grades. Experience has shown that for practical use a soap product which scores 6 or more is bad, 5 is poor, 4 is fair, 3 is good, and 2 or less is excellent. Intermediate clotting scores are indicated by decimals. A soap product which has a clotting score of 6 or more, when thrown onto the surface of water in a dishpan or washing machine, will form large clots which may not dissolve for 30 minutes. One which has a clotting score of 2 or less will dissolve in a minute or two on gentle stirring. A granulated soap product having a clotting score of 3 or less is quite satisfactory and accordingly is non-clotting.

A spray-dried granulated soap product consisting entirely of soap has an unsatisfactory clotting score as shown by the following example.

Example 1

An aqueous slurry of a soap product having the following composition by weight on an anhydrous basis was heated to 200° F. at a pressure of 80 p.s.i.g. and then

spray-dried in a conventional spray-drying tower having an entering air temperature of 200° F.

Components	Percent by Weight
Sodium Soap (92.5% Sodium Tallow Soap and 7.5% Sodium Coconut Oil Soap)	100.0

The spray-dried granulated soap product consisted of mostly scraggly particles and had a clotting score of 4.1.

The addition of an alkali metal xylene sulfonate to the soap, while improving the clotting score, still did not produce a spray-dried granulated soap product having a satisfactory clotting score as illustrated by the following example.

Example 2

An aqueous slurry of a soap product having the following composition by weight on an anhydrous basis was heated to 200° F. at a pressure of 80 p.s.i.g. and then spray-dried in a conventional spray-drying tower having an entering air temperature of 200° F.

Components	Percent by Weight
Sodium Soap (92.5% Sodium Tallow Soap and 7.5% Sodium Coconut Oil Soap)	90.0
Sodium Xylene Sulfonate	10.0
Total	100.0

The spray-dried granulated soap product consisted of mixed puffed and scraggly particles and had a clotting score of 3.6.

The addition of an alkali metal carbonate to the soap also did not produce a spray-dried granulated soap product having a satisfactory clotting score as illustrated by the example below.

Example 3

An aqueous slurry of a soap product having the following composition by weight on an anhydrous basis was heated to 200° F. at a pressure of 80 p.s.i.g. and then spray-dried in a conventional spray-drying tower having an entering air temperature of 200° F.

Components	Percent by Weight
Sodium Soap (92.5% Sodium Tallow Soap and 7.5% Sodium Coconut Oil Soap)	94.0
Sodium Carbonate	6.0
Total	100.0

The spray-dried granulated soap product consisted of mostly scraggly particles and some puffed particles and had a clotting score of 4.6.

The addition of an alkali metal silicate to the soap likewise did not produce a spray-dried granulated soap product having a satisfactory clotting score as shown by the example set forth below.

Example 4

An aqueous slurry of a soap product having the following composition by weight on an anhydrous basis was heated to 200° F. at a pressure of 80 p.s.i.g. and then spray-dried in a conventional spray-drying tower having an entering air temperature of 200° F.

Components	Percent by Weight
Sodium Soap (92.5% Sodium Tallow Soap and 7.5% Sodium Coconut Oil Soap)	93.3
Sodium Silicate	6.7
Total	100.0

The spray-dried granulated soap product consisted of mixed puffed and scraggly particles and had a clotting score of 6.0.

In accordance with the present invention it was found that the tendency of granulated soaps to clot can be reduced greatly to a satisfactory clotting score by the incorporation of a limited amount of an alkali metal xylene sulfonate and either an alkali metal silicate or an alkali metal carbonate in the soap slurry before spray drying.

Accordingly, the present invention provides a spray-dried, non-clotting, granulated soap product consisting essentially of either an alkali metal silicate or an alkali metal carbonate, an alkali metal xylene sulfonate, an alkali metal coconut oil soap, and an alkali metal tallow soap. The invention also provides methods of preparing this product comprising heating an aqueous slurry of the product at atmospheric pressure and then spray-drying the slurry at a higher pressure or heating an aqueous slurry of the product at a pressure above atmospheric pressure and then spray-drying the slurry.

The alkali metal silicate or alkali metal carbonate is present in the soap product in an amount in the range from about 6% to about 18% by weight on an anhydrous basis. Typical alkali metal silicates which may be employed include sodium silicate and potassium silicate. The preferred silicate is sodium silicate. Approximately 6% of sodium silicate is commonly used in commercial granulated soaps to help improve detergency and to help in minimizing corrosion of metals in the washing machine. Typical alkali metal carbonates which may be utilized include, for example, sodium carbonate and potassium carbonate, sodium carbonate being preferred.

The alkali metal xylene sulfonate may be, for example, sodium xylene sulfonate or potassium xylene sulfonate. At least about 2% by weight on an anhydrous basis of the alkali metal xylene sulfonate is present in the spray-dried, non-clotting, granulated soap product. The upper limit of alkali metal xylene sulfonate is not critical, but more than is necessary to achieve the desired non-clotting effect is normally not employed. The maximum suggested amount is about 18% by weight on an anhydrous basis. When the alkali metal xylene sulfonate content is about 6% or above, the granulated soap particles may exist either as scraggly, irregular particles or as rounded or rounded and puffed particles. However, when the alkali metal xylene sulfonate content is less than 6%, it is preferred that the granulated soap particles exist as scraggly, irregular particles rather than as puffed particles in order to insure maximum non-clotting of the particles.

Alkali metal xylene sulfonates are inexpensive substances well known in the chemical industry. They produce no undesirable effect on the appearance or use properties of the granulated soap product. It was found that the incorporation of an alkali metal xylene sulfonate increases the rate at which individual granules dissolve. This is desirable when soap is to be dissolved in lukewarm or cool water.

The mixture of alkali metal coconut oil soap and alkali metal tallow soap amounts to from about 64% to about 92% by weight on an anhydrous basis. Of this amount from about 1% to about 20%, and preferably about 7%, is alkali metal coconut oil soap and from about 99% to about 80% respectively, and preferably about 93%, is alkali metal tallow soap, both soaps being expressed by weight on an anhydrous basis.

The alkali metal coconut oil soap consists of the alkali metal salts of the mixture of fatty acids present in coconut oil. These fatty acids are mainly lauric and myristic acids. Coconut oil, however, also contains caprylic acid, capric acid, palmitic acid, stearic acid, and oleic acid. The alkali metal salts of these acids may be, by way of example, the sodium or potassium salts.

The alkali metal tallow soap is the alkali metal salts of the mixture of fatty acids present in tallow. Tallow consists primarily of palmitic, stearic, and oleic acids,

but also includes a minor proportion of myristic acid. The alkali metal salts of these acids may be, by way of example, the sodium or potassium salts.

It will be appreciated that the spray-dried, non-clotting, granulated soap product may contain a small amount of moisture therein depending upon the desired degree of drying thereof. Minor proportions of other ingredients, commonly used in the soap industry may be included, if desired, such as, perfumes and dyes.

A method of preparing the spray-dried, granulated soap product so that it will have non-clotting, irregular and scraggly shaped particles comprises heating an aqueous slurry of the above soap product to a temperature from about 190° F. to about 215° F. at atmospheric pressure. The aqueous slurry is then spray-dried at a pressure from about 80 p.s.i.g. to about 300 p.s.i.g. and at an entering air temperature of about 200° F. in the spray-drying tower. Another method of preparing the spray-dried granulated soap product so that it will have non-clotting, irregular and scraggly shaped particles comprises heating an aqueous slurry of the above soap product to a temperature from about 190° F. to about 350° F. under a pressure of from about 80 p.s.i.g. to about 300 p.s.i.g. and then spray-drying at an entering air temperature of about 200° F. in the spray-drying tower. The combination of heat and pressure tends to deaerate the slurry and when the pressure is released as when sprayed through a nozzle much of the water is released by flashing and the slurry is separated into many scraggly particles. Since a portion of the water is evaporated by flashing, lower than normal tower temperatures can be used, and this will tend to prevent heat puffing and rounding of the particles. In either process, however, the conventional rate of feed of the aqueous slurry and the conventional amount of air used in atomizing should be carefully controlled to produce consistently irregular and scraggly shaped particles.

The soap product and process of the invention will be further illustrated in connection with the examples below.

Example 5

An aqueous slurry of a soap product having the following composition by weight on an anhydrous basis was heated to 200° F. at a pressure of 80 p.s.i.g. and then spray-dried in a conventional spray-drying tower having an entering air temperature of 200° F.

Components	Percent by Weight
Sodium Soap (92.5% Sodium Tallow Soap and 7.5% Sodium Coconut Oil Soap)	84.0
Sodium Carbonate	6.0
Sodium Xylene Sulfonate	10.0
Total	100.0

The spray-dried granulated soap product consisted of practically all scraggly particles and had a clotting score of 0.6.

Example 6

An aqueous slurry of a soap product having the following composition by weight on an anhydrous basis was heated to 200° F. at a pressure of 80 p.s.i.g. and then spray-dried in a conventional spray drying tower having an entering air temperature of 200° F.

Components	Percent by Weight
Sodium Soap (92.5% Sodium Tallow Soap and 7.5% Sodium Coconut Oil Soap)	86.6
Sodium Silicate	6.7
Sodium Xylene Sulfonate	6.7
Total	100.0

The spray-dried granulated soap product consisted of mixed puffed and scraggly particles and had a clotting score of 2.75.

Example 7

5 An aqueous slurry of a soap product having the following composition by weight on an anhydrous basis was heated to 200° F. at a pressure of 80 p.s.i.g. and then spray-dried in a conventional spray-drying tower having an entering air temperature of 200° F.

	Components	Percent by Weight
15	Sodium Soap (92.5% Sodium Tallow Soap and 7.5% Sodium Coconut Oil Soap)	80.0
	Sodium Silicate	6.7
	Sodium Xylene Sulfonate	13.3
	Total	100.0

10 The spray-dried granulated soap product consisted of mixed puffed and scraggly particles and had a clotting score of 1.0.

Example 8

20 An aqueous slurry of a soap product having the following composition by weight on an anhydrous basis was heated to 200° F. at a pressure of 80 p.s.i.g. and then spray-dried in a conventional spray-drying tower having an entering air temperature of 200° F.

	Components	Percent by Weight
30	Sodium Soap (92.5% Sodium Tallow Soap and 7.5% Sodium Coconut Oil Soap)	75.5
	Sodium Silicate	17.8
35	Sodium Xylene Sulfonate	6.7
	Total	100.0

40 The spray-dried granulated soap product consisted of very scraggly particles and had a clotting score of 1.5.

Example 9

45 An aqueous slurry of a soap product having the following composition by weight on an anhydrous basis was heated to 200° F. at a pressure of 80 p.s.i.g. and then spray-dried in a conventional spray-drying tower having an entering air temperature of 200° F.

	Components	Percent by Weight
50	Sodium Soap (92.5% Sodium Tallow Soap and 7.5% Sodium Coconut Oil Soap)	88.8
	Sodium Silicate	6.7
	Sodium Xylene Sulfonate	4.5
55	Total	100.0

60 The spray-dried granulated soap product consisted of very scraggly particles and had a clotting score of 1.1.

Example 10

65 An aqueous slurry of a soap product having the following composition by weight on an anhydrous basis was heated to 200° F. at a pressure of 80 p.s.i.g. and then spray-dried in a conventional spray-drying tower having an entering air temperature of 200° F.

	Components	Percent by Weight
70	Sodium Soap (92.5% Sodium Tallow Soap and 7.5% Sodium Coconut Oil Soap)	86.4
	Sodium Silicate	11.3
	Sodium Xylene Sulfonate	2.3
	Total	100.0

The spray-dried granulated soap product consisted of very scraggly particles and had a clotting score of 0.6.

Example 11

An aqueous slurry of a soap product having the following composition by weight on an anhydrous basis was heated to 200° F. at atmospheric pressure. The slurry was then spray-dried at a pressure of 80 p.s.i.g. and at an entering air temperature of 200° F. in a conventional spray-drying tower.

Components	Percent by Weight
Sodium Soap (92.5% Sodium Tallow Soap and 7.5% Sodium Coconut Oil Soap)	84.4
Sodium Silicate	11.2
Sodium Xylene Sulfonate	4.4
Total	100.0

The spray-dried granulated soap product consisted of scraggly with some puffed particles and had a clotting score of 2.5.

It will be noted that the spray-dried granulated soap products of the invention illustrated by Examples 5-9 were non-clotting, i.e., they all had a satisfactory clotting score of less than 3.0. In most of these examples, in fact, the clotting score was less than 2.0.

It will be appreciated that many variations and modifications may be made in the soap product and processes of the invention without departing from the spirit thereof. Accordingly, the invention is to be limited only within the scope of the appended claims.

We claim:

1. A spray-dried, non-clotting, granulated soap product consisting essentially of from about 6% to about 18% of a compound selected from the group consisting of alkali metal carbonates and alkali metal silicates, from about 2% to about 18% of an alkali metal xylene sulfonate, and from about 64% to about 92% of a mixture of alkali metal coconut oil soap and alkali metal tallow soap; said mixture of soaps consisting of from about 1% to about 20% of alkali metal coconut oil soap and from about 99% to about 80% of alkali metal tallow soap respectively, all amounts being by weight on an anhydrous basis the alkali metal cation of all of said compounds being selected from the group consisting of sodium and potassium.

2. A spray-dried, non-clotting, granulated soap product as set forth in claim 1 wherein the alkali metal silicate is potassium silicate.

3. A spray-dried, non-clotting, granulated soap product as set forth in claim 1 wherein the alkali metal silicate is sodium silicate.

4. A spray-dried, non-clotting, granulated soap product as set forth in claim 1 wherein the alkali metal carbonate is potassium carbonate.

5. A spray-dried, non-clotting, granulated soap product as set forth in claim 1 wherein the alkali metal carbonate is sodium carbonate.

6. A spray-dried, non-clotting, granulated soap product as set forth in claim 1 wherein the alkali metal xylene sulfonate is potassium xylene sulfonate.

7. A spray-dried, non-clotting, granulated soap product as set forth in claim 1 wherein the alkali metal xylene sulfonate is sodium xylene sulfonate.

8. A spray-dried, non-clotting, granulated soap prod-

uct as set forth in claim 1 wherein the alkali metal coconut oil soap and the alkali metal tallow soap are sodium coconut oil soap and sodium tallow soap.

9. A spray-dried, non-clotting, granulated soap product consisting essentially of from about 6% to about 18% of a compound selected from the group consisting of alkali metal carbonates and alkali metal silicates, from about 2% to about 18% of an alkali metal xylene sulfonate, and from about 64% to about 92% of a mixture of alkali metal coconut oil soap and alkali metal tallow soap; said mixture of soaps consisting of about 7% of alkali metal coconut oil soap and about 93% of alkali metal tallow soap, all amounts being by weight on an anhydrous basis the alkali metal cation of all of said compounds being selected from the group consisting of sodium and potassium.

10. The method of preparing a spray-dried, non-clotting, granulated soap product having irregular and scraggly shaped particles comprising heating to a temperature in the range from about 190° F. to about 215° F. at atmospheric pressure an aqueous slurry of from about 6% to about 18% of a compound selected from the group consisting of alkali metal carbonates and alkali metal silicates, from about 2% to about 18% of an alkali metal xylene sulfonate, and from about 64% to about 92% of a mixture of alkali metal coconut oil soap and alkali metal tallow soap, said mixture of soaps consisting of from about 1% to about 20% of alkali metal coconut oil soap and from about 99% to about 80% of alkali metal tallow soap respectively; and spray drying the slurry at a pressure from about 80 p.s.i.g. to about 300 p.s.i.g.; all amounts being by weight on an anhydrous basis and the alkali metal cation of all of said compounds being selected from the group consisting of sodium and potassium.

11. The method of preparing a spray-dried, non-clotting, granulated soap product having irregular and scraggly shaped particles comprising heating to a temperature in the range from about 190° F. to about 350° F. under a pressure of from about 80 p.s.i.g. to about 300 p.s.i.g. an aqueous slurry of from about 6% to about 18% of a compound selected from the group consisting of alkali metal carbonates and alkali metal silicates, from about 2% to about 18% of an alkali metal xylene sulfonate, and from about 64% to about 92% of a mixture of alkali metal coconut oil soap and alkali metal tallow soap, said mixture of soaps consisting of from about 1% to about 20% of alkali metal coconut oil soap and from about 99% to about 80% of alkali metal tallow soap respectively; and spray drying the slurry; all amounts being by weight on an anhydrous basis and the alkali metal cation of all of said compounds being selected from the group consisting of sodium and potassium.
